PNEUMATIC CONTROL FOR AIR SUPPLIED
TO A STOKER

Lawrence R. Teeple, Portland, Oreg.

Application July 17, 1934, Serial No. 735,617

7 Claims. (Cl. 110—69)

This invention relates generally to underfeed stokers, and particularly to a means for automatically controlling the amount of air supplied to the combustion.

5 The main object of this invention is the provision of an exceedingly simple and efficient form of control for the air delivered by the stoker to the combustion zone of a furnace.

The second object is to provide a control means 10 to be efficient in its operation, devoid of complications and at the same time capable of providing any desired amount of lag between the commencement of fuel delivery and that of air delivery.

15 These, and other objects, will become more apparent from the specification following as illustrated in the accompanying drawings, in which Fig. 1 is a perspective view of an underfeed stoker equipped with my device.

20 Fig. 2 is a section taken along the line 2—2 in Fig. 1 showing the pilot damper partly open.

Fig. 3 is a section taken along the line 3—3 in Fig. 1 showing the butterfly damper partly open.

25 Fig. 4 is a somewhat diagrammatic view showing the relation of the parts in detail with the distance between the elements greatly reduced.

Fig. 5 illustrates the internal structure of the air valve mechanism showing a position which 30 the parts can assume under conditions different than those which are illustrated in Fig. 4.

Similar numbers refer to similar parts throughout the several views.

Referring in detail to the drawings, there is 35 shown an underfeed stoker including the fuel hopper 10, the fuel feeding tube 11 and retort 12, to which fuel is delivered from the hopper 10 through the tube 11 by means of a motor 13 which operates a screw (not shown) within the 40 tube 11. The motor 13 also operates a fan within the casing 14 and which delivers air through the air duct 15 to the tuyère base 16 which supports the retort 12.

Referring more particularly to my invention 45 same will be seen to consist of an air compressor unit 17 which is also driven from the motor 13, the pilot damper 18 and the butterfly damper 19. The air compressor 17 may of course be of any desired type, but for the purpose of illustration 50 there is shown a cylinder 20 within which operates a piston 21.

The piston 21 is operated by an eccentric 22 which is supported by the compressor block 23. The eccentric 22 acts directly against a roller 24 55 which is carried by the piston 21. The spring 25

holds the roller 24 against the eccentric 22 and an adjustment is provided for the spring 25 in the form of a set screw 26. Air is admitted to the compressor by the laterally extending pipe 27 which communicates with an air filter 28. 5

The discharge end of the cylinder 20 is closed by a bushing 29 which forms a head therefor. Within the bushing 29 is disposed a ball check 30 which closes on the intake stroke of the compressor and forces the incoming air to be drawn 10 through the filter 28. The compressed air is discharged through a pipe 31 into an oil filter 32 which may be of any suitable type, preferably a simple container in which is disposed a fabric covered cage through which the air 15 passes for the purpose of removing oil therefrom, from which it passes through a throttle valve 33 provided with an adjusting screw 34. The compressed air is then carried to the T fitting 35, one opening of which communicates 20 with the bellows 36 which is supported by the bracket 37 within the casing 38.

The bellows 36 actuates a rack 39 which meshes with a pinion 40 secured on the shaft 41 of a butterfly damper 19 which can substantially close 25 the air duct 15 when normal thereto.

The operation of this portion of the device is as follows: When the stoker motor 13 is operated, air will flow through the fitting 35 into the bellows 36, causing it to open the butterfly 30 damper 19 and to remain open unless otherwise effected, as will be explained later.

It is desirable to provide a spring 42 within the casing 43 for returning the rack 39 to the position shown in Fig. 4. 35

Turning now to the pilot damper 18 it will be seen that same is secured to the shaft 44 on which is secured a slotted indicator plate 45 from which projects a pointer 46 which is disposed alongside of the graduated cam 47, to which it is adjustably secured by means of the clamping screw 48. The end 49 of the cam 47 constitutes a drop off or a low point, the purpose of which will be explained presently.

The members 45 and 47 are mounted within a 45 casing 50 which supports a pivot 51 on which are pivotally mounted the spring-urged arm 52, one end of which rides against the cam 47 and the other end of which is acted upon by a spring 53 which reacts against a second arm 54 which engages a grooved collar 55 on the stem 56 which carries an air valve disk 57. The disk 57 seats over the outlet 58 of an air line 59 which connects with the side outlet of the T fitting 35. 50

The air line 59 is provided with a valve 60 hav- 55

ing a relief opening 61 which is adjustably controlled by means of the set screw 62. It is necessary to provide an outlet opening 63 by means of which air can escape from the outlet 58 when 5 the disk 57 is withdrawn therefrom.

The operation of the device is as follows: Assuming that the stoker motor 13 is started in response to any of the usual controls, the pilot damper 18 having been at rest and the butterfly damper 19 being closed (as shown in Fig. 4) as the compressor 17 is operated and pressure builds up in the fitting 35 the bellows 36 becomes distended, moving the rack 39 and opening the butterfly damper 19, and the pilot damper 18 is raised by the air flowing past the butterfly damper. This, however, does not happen instantaneously, there being an appreciable amount of time between the moment the stoker starts feeding coal and the moment it starts feeding air, and this time can be varied, as will be explained.

As the pilot damper 18 continues to rise, under the increasing flow of air permitted by the gradually opening butterfly damper 19, the cam 41 is carried with it—that is, the end 49, whose position can be regulated by the screw 48, descends to a point which will permit the end of the arm 52 to move, under the influence of the spring 52—A, and, through the arm 54, open 30 the outlet 58.

While the compressor 17 is sufficiently large to overcome the leak at the outlet 61 to the extent of operating the bellows 36, it is not able to do so when the outlet 58 is open, as stated, causing 35 the butterfly damper 19 to be moved in a closing direction, under the influence of the spring 42, until the butterfly 19 reduces the air flow sufficiently to bring about a sufficient drop of the damper 18, which will cause the cam 41 to again 40 close the outlet 58.

It can be seen from the foregoing that there is produced by this arrangement a balanced condition—that is, the attendant merely sets the indicator pointer 46 at the desired mark on the graduated cam 47, which represents a predetermined air flow, and this flow is maintained within very close limits, due to the fact that when the flow exceeds a predetermined maximum the outlet 58 will be opened and the damper 19 will be moved toward a closed position, and when the flow falls below a predetermined minimum the outlet 58 will be closed, causing the damper 19 to be moved toward an opening position.

It might seem that this would bring about a 55 rapid and continuous adjustment of the setting of the butterfly damper, but such is not the case in actual practice since the action is by no means instantaneous, the adjustments being slow and positive.

The purpose of the relief opening 61 which, as stated, is not large enough to prevent the functioning of the bellows 36, is to gradually relieve the pressure from the line 59 whenever the air flow through the duct 15 stops completely, due 65 to a stoker shut-down and the damper 18 is in the position of rest (as shown in Fig. 4).

Unless this relief opening 61 was present, or there was not enough natural leakage in the system, then the butterfly damper 19 could remain in a partially open position during the shut-down so that the next time the stoker was operated air would immediately pass the butterfly 70 19 and open the damper 18, producing an undesirable result, namely the delivery of air simultaneously with the delivery of fuel, causing the

lighter particles to be blown out of the retort 12 before they could be protected by the incoming green fuel.

It is for this reason that it is desirable to postpone the first delivery of air until after the coal-feeding operation is well under way.

The amount of lag can be controlled by the adjustment of the screw 34 which does not effect the pressure within the bellows 36, but the rate of air flow thereto.

10

I claim:

1. A pneumatic control for air supply to a stoker consisting of an air duct having a pilot damper mounted therein whose position is responsive to the flow of air through said duct, a control damper within said duct for controlling the flow of air therethrough, a pneumatic actuator for said control damper, an air supply controlled by the operation of said stoker for operating said damper actuator, and a cam operated valve actuated by said pilot damper for controlling the pressure of air in said damper actuator.

2. The device described in claim 1, including means for relieving the air pressure from the 25 damper actuator when the pilot damper is at a position of rest.

3. A device of the class described, the combination of a fan, a motor for driving said fan, an air duct conveying air delivered by said fan, a pilot damper within said duct actuated by air passing therethrough, an adjustable cam actuated by said pilot damper, an air valve operated by said cam, a control damper mounted in said duct for controlling the flow of air therethrough, 35 a rack and pinion for operating said control damper, an air operated actuator for said rack controlled by said air valve, an air compressor operated by said motor for delivering air under pressure to said actuator, said air valve constituting a means for relieving the pressure from said actuator when said pilot damper is raised above a predetermined position by an excessive flow of air through said duct.

4. The device described in claim 3, together 45 with a means for continuously relieving the pressure from said actuator at a rate intermediate the rate of delivery by said compressor and the rate of flow through said pilot damper-actuated air valve.

5. The device described in claim 1, together with means for regulating the amount of air which can be delivered by said compressor to said damper actuator.

6. A pneumatic control for air supplied to 55 stokers comprising an air duct having a butterfly damper for regulating the amount of air flowing through said duct, a pilot damper which is free to swing in said duct under the influence of air passing said butterfly damper, a pneumatic actuator for opening said butterfly damper during the operation of the stoker in connection with which this device is used, spring means for closing said butterfly damper in opposition to said pneumatic actuator, a source of compressed air 60 connected to said actuator by means of a pipe, an air valve communicating with said pipe between said butterfly actuator and its source of air supply, means operated by said pilot damper for opening said air valve during the passage of an 70 excessive amount of air through said duct and closing said air valve during the passage of a quantity of air which is less than a predetermined minimum, a throttle valve between the source of air supply and said actuator for retarding the 75

opening of said butterfly damper for a predetermined period after the commencement of air delivery to said butterfly actuator.

- 5 7. In a stoker the combination of an air supply duct having a fan for supplying combustion air thereto, a pilot damper in said duct responsive to the flow of air therethrough, a control damper within said duct for controlling the flow of air therethrough, a pneumatic actuator for said con-

trol damper, means for delivering air to said actuator when said fan is operating, an air valve actuated by said pilot damper for releasing air through said actuator when the velocity of the air exceeds a chosen value, and means for bleeding air from said actuator to permit the control damper to close upon cessation of air flow to the actuator.
